Application September 11, 1945, Serial No. 615,538

23 Claims. (Cl. 332—13)

1

This invention relates to an electron beam producing apparatus. More particularly it relates to a cathode ray tube for directly converting variable continuous energy waves into proportionally variable time spaced pulses. Such a tube, for example, may be used in electrical multichannel signal transmission systems employing time-modulated pulses as described in our copending application, for "Multichannel Pulse Modulator," Serial No. 567,414, filed December 9, 1944, now Patent No. 2,495,738, granted January 31, 1950, of which this invention is an improvement.

It is an object of this invention to convert continuous energy variations into directly proportional time-displaced pulses in a simple, accurate, and effective manner.

Another object is to convert such energy variations into time-displaced pulse variations by means of a cathode ray tube.

Another object is to compensate for the distortion due to special geometry of such a tube in order to obtain a direct linear relationship between the amount of such energy variation and the time displacement of corresponding pulses.

Another object is to provide means to decrease the amount of energy required to produce a response in the tube and to increase the functional accuracy of such a cathode ray tube.

Another object is to produce pulses of substantially equal duration.

Another object is to decrease the distortion obtained in the type of cathode ray tube disclosed in the above-mentioned copending application.

Another object is to improve and simplify multichannel transmission systems.

Another object is to provide an improved modulator device.

Another object is to provide a multichannel transmitter which requires less equipment, fewer tubes, and is more economical to build and maintain than prior multichannel transmitters.

Another object is to prevent cross-talk in multichannel transmission systems.

Still other objects will appear from time to time in the description which follows.

One of the features of this invention is the employment of a cathode ray tube or other electron beam-producing apparatus having means to cause the beam to sweep through a given movement, together with a series of special electrodes which coat with the beam and a target assembly arrangement to produce time dis-

2

placed pulses. When energy, such as a signal is applied to any one of the special electrodes in the tube, the beam is deflected from the path of its normal sweep movement by an amount corresponding to the amount of this energy. Each electrode may comprise a separate signal channel. The target assembly is arranged to present a plurality of electron-responsive areas, one for each of said special electrodes. These areas are arranged in series relation so as to be traversed in succession by the beam during its sweep movement. The areas when traversed by the beam produce pulse flow of electrical energy by secondary emission. To effect time modulation of the pulse energy, the target assembly comprises a shielding means having a series of long and narrow apertures or slots disposed at acute angles to the direction of the beam deflection. The sweep of the beam traverses the beam responsive area behind the shielding means through the apertures sooner or later in time depending upon the amount of energy or signal applied to the special electrodes which controls deflection of the beam. Thus the output pulse energy for each signal is time displaced relative to an average time position according to the instantaneous value of the modulating signal.

In a cathode ray tube wherein the sweep circuit causes the electron beam to rotate around the tube at a constant angular velocity and the deflecting electrodes for the beam deflect it radially toward and away from the geometric center of the tube, there is a difference in the circumferential velocity of the end of the beam depending upon its deflection. In order to compensate for this difference and the tube geometry so that the beam will traverse the beam responsive area through the slot in a direct time-space relationship to the amount of energy causing the deflection, the aperture must be properly shaped and/or positioned across the path of the end of the beam. The theoretical line across the target area which will produce time spaced pulses directly proportional to the energy for radially deflecting the beam, may be mathematically calculated. This line is not a straight line, but a curved one which in some cases may be more complex than a simple arc. In calculating the shape and position of this line, both the circumferential movement and the radial deflection movement of the beam are considered. Thus, to directly and linearly time-displace the variations in deflecting energy with the motions of the beam, the target area or aper-

ture, should be positioned and spaced to cover substantially all of this calculated curved line. Two methods for doing this are: (1) to provide a curved aperture to uniformly bracket the theoretical line; and (2) to use a straight and narrow slot so positioned substantially as to cover and bracket the curved line.

The long and narrow apertures include end portions disposed parallel to the direction of the signal beam deflection, i. e., substantially radial, so as to provide maximum limits of pulse displacement. This prevents break through from one channel to the next when signals of unusually high value occur.

The target assembly, comprising the apertures and/or the beam responsive means, may be positioned substantially perpendicular to the beam, such as by forming it out of obtuse conical plates.

The electron beam may be commutated into beam segments, one corresponding to each of the deflection plates connected to each signal channel. This may be accomplished by either providing a commutating plate with apertures through which the beam travels, or by means of commutation keying of the grid, on control electrodes of the cathode ray tube whereby the beam is divided into segments for modulating treatment by the signals to be transmitted. This feature of providing individual beam segments is important in avoiding cross-talk that may otherwise occur if the deflection produced by signals of one channel were permitted to be carried over by the beam to the next deflecting zone of the adjacent channel.

The deflecting electrodes may be extended a considerable distance parallel to and along the path of each beam segment so that a lower voltage may be used to produce a given deflection of the beam. This in turn reduces the acceleration of the electrons in the beam so that they will be deflected more by smaller changes in energy in the signal. Such electrodes may be cylindrical, frusto-conical, or both, and are preferably flared at their target ends to permit free deflection of the beam passing between them.

Another feature of this invention for use in deflecting the beam segments in response to signal energy comprises varying the acceleration of each beam segment in accordance with the signal energy, then passing the beam through a constant deflecting potential.

The above and other objects and features of the invention will become more clear upon consideration of the following detailed description to be read in connection with the accompanying drawings, in which:

Fig. 1 is a diagrammatical illustration of a multichannel pulse time modulator according to the principles of this invention;

Fig. 2 is a geometric diagram of a theoretical time-space deflection line on the target and relative to the shape and position of a target area of one embodiment of this invention;

Fig. 3 is a graphic representation of the time modulated operation and the shape of the arcuate target area of another embodiment of this invention;

Fig. 4 is a graphical illustration showing a period of multichannel pulses and of control wave employed in the modulator;

Fig. 5 is a longitudinal section of a cathode ray tube of a further embodiment of this invention; and

Fig. 6 is a diagrammatic showing of still another embodiment of the modulator of this invention.

Referring to Figs. 1 and 4, a multichannel pulse time modulating system is shown for eleven signal channels, 1 to 11 and a synchronizing channel 12. One period or cycle of multichannel pulses is shown in graph b of Fig. 4, the pulses of signal channels 1 to 11 being of a given pulse width and the synchronizing pulses 12 being of a greater pulse width, whereby the latter can be separated from the signal channel pulses at the receiver by a suitable pulse with discriminator.

While this system is shown for 12 channels in all, it will be understood that a great many more channels may be provided, (for example, such as 24 channels) the number per modulator tube being limited largely by the size of the tube, the character of sweep movement selected from the beam, the maximum time displacement per channel, the guard intervals between pulses of adjacent channels and the widths of the pulses.

Referring more particularly to Fig. 1, a modulator is shown in the form of a cathode ray tube 13. While this form of modulator is shown to illustrate the invention, it will be understood that other forms of electron beam producing arrangements may be employed; also it will be understood that the tube illustrations in other figures are purposely exaggerated as to the relative proportions and spacing of elements to assist in explaining the principles of the invention, and therefore the illustrations generally do not represent the ultimate proportions desired for commercial embodiments.

The tube 13 contains electron beam producing elements 14, 15 and 16, preferably of the character capable of producing a fine beam of electrons. The beam of electrons is caused to have a sweep movement by means of horizontal and vertical (x-axis and y-axis) deflecting plates 17, 18 and 19, 20. The sweep movement chosen for the purpose of illustrating the present invention is circular and the deflecting waves for producing this sweep movement are obtained from an oscillator 21 and a phaser 22. The control waves obtained from phaser 22 are represented in graph a of Fig. 4 by sine waves 23 and 24, separated in phase by 90°. Sweep movements other than circular may be used, for example, a sweep pattern such as used in television scanning may be employed.

A commutator plate 25 having a series of apertures 26, 27, etc., arranged in a circular manner divides the beam during its sweep movement into segments. The apertures for the signal channels are preferably shaped in the form of sectors, the sides thereof being defined by radii of the plate 25. This shape, however, is not essential except where a maximum number of channels is required. The aperture 28 for the synchronizing channel need not be of this shape even where a maximum number of channels is desired; it may instead be of narrow rectangular form.

To effect signal deflection of the beam segments, a frusto-conical electrode 29 is provided with a series of small leaf electrodes 30, 31, etc., disposed in series relation about the edge of the electrode 29. The electrodes 30, 31 are arranged so that the corresponding beam segments passed by apertures 26, 27, etc., occur between them and the central electrode 29. The signal is applied to the small electrodes; the electrode 30 being connected to the input circuit of channel 1 as indicated at 32. The input signal is preferably stepped up by transformer 32a before application to the electrode.

The target assembly with which the electrons

of the beam cooperate to produce pulse energy flow comprises a shielding, or modulator plate 33 and an electron responsive area or secondary electron emission ring 34. The potential of the plate 33 is maintained higher than that on the ring 34 so that when electrons impinge upon the ring 34, the ring emits electrons which flow to the plate 33. The plate 33 is provided with long and narrow slots 35, 36, etc., one for each channel, for passage of the beam for impingement upon the area of ring 34. The central portion of the slots for the signal channels are preferably disposed at an acute angle with respect to the direction of signal deflection produced by the potential differences between the electrodes 30, 31, etc., and central electrode 29. The end portions of the slots, however, are disposed parallel to the direction of signal deflection. The slot 37 for the synchronizing channel is disposed parallel to the direction of signal deflection. This relationship of the slots of plate 33 and the beam sweep movement is shown on a larger scale in Fig. 2.

Referring to Fig. 2, a segmented beam of electrons is shown by dotted line 38 passing between the deflection electrodes 29 and 30. This beam 38 may be deflected from its original arcuate path 39, across the sector θ of a given channel target area on the plate 33 through an angle φ between the longer arcuate path 40 and the shorter arcuate path 41, respectively. Since the angular velocity of the beam 38 is constant, the velocity of the end of the beam along arc 40 would be much greater than along arc 41 or even an intermediate arc 39. Thus, a straight slot proportioned along line 42 from the lower left corner of the sector channel to the upper right corner thereof, would not time space impulses onto the beam responsive means (not shown in Fig. 2) directly proportional to the radial deflection of the beam 38. The path of the mathematically calculated directly proportional time-space deflection line across the channel sector is shown as arcuate line 43. Thus, in order to position a straight long and narrow slot of given width, such as aperture or slot 35, to cover substantially the line 43, it must be moved both a little to the left and at an angle to the line 42 as shown.

Another way of forming a target area or slot which will cover the theoretical line 43 is to make the aperture arcuate and similar to that of the line 43 such as that shown in Fig. 3. The dotted line 44 in Fig. 3 represents the sweep path of the beam 38 in the absence of signal modulation. It will be noted that this path traverses the center of the central portion 45 of the arcuate aperture 46. The beam for this normal sweep movement causes secondary emission of electrons from plate 34, thereby producing a pulse flow of energy substantially as indicated at 47.

Assume now that a signal occurs on electrode 30 of a positive value such as to cause a deflection of the beam 38 to the path indicated at 48. This will produce a pulse flow displaced from the pulse timing at 47 as indicated at 49. The radially outward extended portion 50 of the slot 46 is provided as hereinbefore stated to limit the time displacement for exceptionally large signal values. The output pulse such as indicated at 49 will occur for any displacement of the beam along the length of portion 50. If the aperture 46 were terminated at the end of the central portion 45 no output pulse would be obtained for a signal causing deflection beyond such end.

For a negative swing of signal on electrode 29 the beam 38 will be shifted to a path inward of the path 44. Such a negative swing may be represented by the path 51, the corresponding output pulse being represented at 52. The radial portion 53 of the aperture 46 provides a maximum negative displacement for the pulse similarly as in the case of the outward end portion 50. The aperture 37 for the synchronizing channel is shown in Fig. 3 to be a radial narrow slot, although it may take the form of a small square aperture since for the synchronizing channel no deflecting potential need be provided. The aperture 37 preferably is elongated as shown to accommodate any offset bias that may be normally imposed upon the system, such for example as by controlling the amplitude of the deflecting waves supplied to electrodes 17 to 20.

Both the apertures 35 (previously mentioned) and 46 may be tapered slightly wider at their outer ends along lines 48 and 49 than at their inner end along lines 41 and 51, respectively, to compensate for the difference in circumferential velocity of the beam along these lines and thereby produce impulses of equal duration for any deflection.

Referring back to Fig. 1, the potentials applied to the different elements of tube 13 are indicated. The elements 17, 20, 25, 29 and 33 are all provided with the same high voltage potential as indicated at 54. The control grid 15 is shown to be provided with a high negative voltage by connection 55 while the cathode element 14 is provided with a less negative voltage by the interposition of a resistor 56. The beam shaping or focusing element 16 is provided with a more positive potential than the cathode 14 by means of resistors 57 and 58. The anode target ring 34 is provided with a less positive potential than the modulating plate 33 by means of the interposed resistors 59, 60 and 61. The output of the circuit elements 33, 34 is applied to a cathode follower 61, the output energy of which may be applied to the usual carrier frequency modulator for transmission. It will be noted here that this output circuit is independent of the electron beam circuit. This is of advantage because the secondary emission function of the elements 33 and 34 is in effect an amplification of the signal energy. For example, the targets may be made a part of the beam circuit whereby the beam current controls the output of the tube. In such cases, however, the beam current controls and in order to get desired amplification amplifiers are required.

From the foregoing description it can be readily seen that the combination of the apertures or slots of the modulation plate 33 and the anode ring 34 provide the pulse generation, and the sequential distribution shape and position of the apertures provide the necessary delay or phase difference between the pulses of adjacent channels. The deflection system 29, 30, 31, in conjunction with the shape of the apertures of the modulator plate 33 provide the modulation translation of signal increments from amplitude variations into time displacements of pulses.

Further, the shape and position of the apertures of plate 33 allows modulation limitation for each channel. The width of the apertures of plate 33 determines the width or duration of the channel and synchronizing pulses, the aperture for the synchronizing channel being wider, distinguishes the synchronizing pulses from the signal channel pulses. Finally the combinations

of the modulator plate 33 and the anode ring 34 provides for the mixing of the channel and synchronizing pulses into a single train of pulses for transmission. Such a train of pulses is shown in graph *b* of Fig. 4, the period of which corresponds to the period of the beam control waves shown in graph *a*.

Referring now to Fig. 5, the location of the elements of tube 13 shown in Fig. 1 are all proportionally placed and the respective shape and form of the electrodes 29 and 30 are more clearly shown. The center and major electrodes 29 comprise two axially adjacent frusto-cones having spaced around it the minor electrodes 30, 31, etc., formed of strips bent near their center so as to be spaced a greater distance from the electrode 29 at the outgoing end of the beam 38 than at the ingoing end for that beam. This particular structure, however, is not limiting. Any similar structure which permits free deflection of the beam 38 as well as paralleling the beam for a comparatively long distance may be found advantageous and desirable.

Either or both the modulating plate 33 and secondary electron emission ring 34 shown in Fig. 1 may be replaced by the obtuse conically shaped plates 62 and 63 (shown in Fig. 5) respectively mounted perpendicularly to the target end of the electrode beam 38. The use of conically shaped plates 62 and 63 eliminates the factor of the secant of the angle α , between the axis of the tube and the deflection due to the sweep movement of the beam 38, from the calculation of the theoretical time space deflection line 43.

In Fig. 6 is shown still another alternative form of modulator. The modulator tube 13b differs from the tube 13 of Fig. 1 in that the grid is keyed according to a commutating control wave which replaces the commutator plate 25 used in the tube of Fig. 1, and the signal deflecting arrangement is replaced by a signal acceleration-deflection system. The commutation control of the grid 15 keys the beam on and off according to the channel timing desired. This is accomplished by applying the base wave of oscillator 21 to a multiplier 64 to obtain the proper channel frequency. The output wave of multiplier 64 is phased at 65 and applied to a shaper 66 which may be a multivibrator or other wave shaping means capable of transforming a sine wave into a substantially rectangular wave form. The rectangular wave thus obtained is applied to the grid 15 which is normally biased to cut off.

The signal acceleration-deflection of the beam is effected by first providing a cylindrical electrode 67 spaced from an annular electrode 68 between which a potential difference is applied as indicated at 69. The potential difference between these two elements provides a constant deflection force for the beam passing therebetween. Each signal channel is provided with a hollow cylindrical element, such as indicated at 70 for channel 1, through which a beam segment passes, once for each sweep cycle of the beam. It will be understood of course that the sweep movement will be synchronized with the keying operation so that a beam segment occurs in proper time relation for each of the hollow cylindrical electrodes of the several signal channels. As the beam segment flows through the hollow cylinder 70 the potential applied thereto will accelerate or decelerate the electrons according to the value of the signal applied. A given positive bias may be applied as indicated at 71 for each channel so that the positive and negative values

of signals will cause the electrons of the beam to accelerate and decelerate proportionately. This change in acceleration of the beam of electrons coacts with the constant deflecting potential of electrodes 67 and 68 to vary the amount of deflection of the beam relative to the apertures of the modulator plate 33. It will be clear that this variation is effected in accordance with the signal and that the output pulse is time displaced in proportion to the signal value.

Another modification shown in Fig. 6 is that the two electrodes 67 and 68 are cylindrical in shape and that they produce a different shaped pattern on the plate 33 than that previously disclosed. In this case the theoretical curved time spaced deflection line on the target area is in the shape of an S, so S-shaped apertures 72 are shown on the plate 33 in Fig. 6. However, instead of the S-shaped apertures, straight slots 20 may be used which are positioned to cover substantially this theoretical line as in the embodiment shown in Fig. 2.

It will be understood that the keying of the beam by means of the grid 15 may also be applied to the system shown in Fig. 1 in place of the commutator plate 25 shown therein.

Further it will be understood that any one or more of the different features disclosed in the different modifications may be employed in any one or several different cathode ray tubes. Also, many additional variations and arrangements of the tube elements and associated circuits are possible without departing from the invention. For example, the beam may be shaped prior to its deflection, thereby doing away with special shaped flat apertures in plate 33, as is more fully described in our copending application referred to above.

It is accordingly stressed that the different embodiments herein shown and described are intended for illustration purposes only and not as a limitation on the scope of the invention as set forth in the objects and the accompanying claims.

We claim:

1. A cathode ray tube comprising: means to produce a beam of electrons, means to cause said beam to have a circular sweep movement, means to divide the beam into a successive plurality of segments with respect to said sweep movement, a deflecting electrode arranged along the path of each said beam segment to control radial deflection of that beam segment, separate means for applying energy to each said electrode, means responsive to said beam segment, and shielding means positioned between said beam responsive means and said deflecting electrodes, said shielding means having long and narrow arcuate apertures therein corresponding to each beam segment through which said beam segments pass, said apertures being shaped and positioned to cover substantially the curved theoretical time-shaped deflection line calculated to compensate for the different circumferential sweep velocities of said beam segments, so that the energy of each beam segment is transmitted successively to said beam responsive means in time spaced relationship directly proportional to the amount of energy applied to said deflecting electrodes whereby distortion of this proportion due to said different velocities of said beam segments is prevented.

2. A cathode ray tube comprising: means to produce a beam of electrons, means to cause said beam to have a circular sweep movement, means to divide the beam into a successive plurality of

segments with respect to said sweep movement, a deflecting electrode arranged along the path of each said beam segments to control the radial deflection of that beam segment, separate means for applying energy to each of said electrodes, means responsive to said beam segments, and a shielding means positioned between said beam responsive means and said deflecting electrodes, said shielding means having apertures therein corresponding to each beam segment through which that beam segment passes, each of said apertures being long and narrow and disposed at an acute angle to the radius through the center of said tube and spaced slightly in the opposite direction from the sweep movement of said beam segment whereby the theoretical time spaced deflection curved line for traverse by the end of said beam segment is substantially bracketed so that the energy from each said beam segment is transmitted successively to said beam responsive means in a time spaced relationship substantially directly proportional to the amount of energy applied to said deflecting electrodes.

3. A cathode ray tube comprising: means to produce a beam of electrons, means to cause said beam to have a circular sweep movement, means to divide the beam into a successive plurality of segments with respect to said sweep movement, means arranged along the path of each said beam segment to control the radial deflection of that beam segment, separate means for applying energy to each of said last mentioned beams, means responsive to said beam segment, and shielding means positioned between said beam responsive means and said deflecting means, said shielding means having apertures therein through which said beam segments pass, said apertures being so shaped and so positioned with respect to the motion of said beam segments to transmit energy in each beam segment successively to said beam responsive means in a time spaced relationship substantially directly proportional to the amount of energy applied to said deflecting means, said deflecting means including a major electrode disposed centrally of the sweep path of said beam and a plurality of minor electrodes disposed in sequential relation along the sweep path of each said beam segment and spaced from said major electrode; and said beam responsive means having the form of an obtuse cone positioned axially of said tube, the conical sides of which are substantially perpendicular to said beam as it is deflected around the tube.

4. A cathode ray tube comprising: means to produce a beam of electrons, means to cause said beam to have a circular sweep movement, means to divide the beam into a successive plurality of segments with respect to said sweep movement, means arranged along the path of each said beam segment to control the radial deflection of that beam segment, separate means for applying energy to each of said last mentioned means, and means responsive to said beam segments; said means for controlling the deflection of said beam segments including a major electrode disposed centrally of the sweep path of said beam and a plurality of minor electrodes disposed in sequential relation along the sweep path of each said beam segment and spaced from said major electrode; and said beam responsive means having the form of an obtuse cone positioned axially of said tube, the conical sides of which are substantially perpendicular to said beam as it is deflected around the tube.

5. A cathode ray tube comprising: means to

produce a beam of electrons, means to cause said beam to have a circular sweep movement, means to divide the beam into a successive plurality of segments with respect to said sweep movement, means arranged along the path of each said beam segment to control the radial deflection of that beam segment, separate means for applying energy to each of said last mentioned means and means responsive to said beam segments, said means for controlling the deflection of said beam segments including a major electrode disposed centrally of the sweep path of said beam and a plurality of minor electrodes disposed in sequential relation along the sweep path of each said beam segment.

6. The cathode ray tube of claim 5, wherein said minor electrodes are spaced from said major electrode so as to be a greater distance from the major electrode as its beam outlet end than at its beam inlet end to provide passage for the beam and its deflection therebetween.

7. The cathode ray tube of claim 5, wherein said major electrode is at least partially frustoconical in shape.

8. The cathode ray tube of claim 5, wherein said major electrode is at least partially cylindrical in shape.

9. A cathode ray tube comprising: means to produce a beam of electrons, means to cause said beam to have a circular sweep movement, means to divide the beam into a successive plurality of segments with respect to said sweep movement, a deflecting electrode arranged along the path of each said beam segments to control the radial deflection of that beam segment, separate means for applying energy to each of said electrodes, and means responsive to said beam segments having the form of an obtuse cone positioned axially of said tube, the conical sides of which are substantially perpendicular to said beam segment as it is deflected around the tube.

10. In a beam tube having an envelope, means therein providing a source of electrons, means forming the electrons into a beam, means including electrodes arranged about the beam in space quadrature for deflecting the beam, and a target electrode, the combination of sets of deflecting electrodes positioned substantially in said certain deflected paths of the beam and an output electrode having elongated and tapered slots for passing the deflected beam positioned between said last mentioned deflecting electrode and the target electrode, said output electrode having a surface at which the beam arrives which is shaped to be substantially perpendicular to the beam in its different deflected positions.

11. A beam tube according to claim 10, wherein in the target electrode has a surface at which the beam arrives which is shaped to be substantially perpendicular to the beam in its different deflected positions.

12. A beam tube according to claim 10, wherein the deflecting electrodes of the several sets comprise a frusto-conical common electrode and an electrode individual to its set, said last mentioned electrode being elongated and tapered and arranged along and in spaced relation to the curved surface of the common electrode.

13. A multichannel pulse modulator comprising means to produce a beam of electrons, means to cause said beam to have a circular sweep movement, a plurality of signal channel input circuits, means associated with said input circuits to control deflection of the beam successively during its sweep movement according to increment of the

input signal of said circuits, and beam responsive means to provide pulses of energy modulated according to the corresponding signal deflection of said beam; said beam responsive means including a shielding means having apertures therein through which said beam passes, said apertures being so proportioned respecting length and breadth and so positioned with respect to the motion of said beam to transmit the energy from the beam through each aperture successively in time space relationship substantially directly proportional to the amount of energy applied to said means for deflecting said beam and said apertures being so shaped that they transmit equal amounts of energy at all deflection positions of said beam therealong.

14. A multichannel pulse modulator comprising: means to produce a beam of electrons, means to cause said beam to have a circular sweep movement, means to divide the beam into successive plurality of segments with respect to said sweep movement, a plurality of signal channel input circuits, means associated with said input circuits to control deflection of the beam segments successively during their sweep movement according to the increment of the input signal of said circuits, means responsive to said beam segments, and shielding means positioned between said beam responsive means and said means to control deflection of said beam segments; said shielding means having long and narrow arcuate apertures therein corresponding to each beam segment through which said beam segments pass, said apertures being shaped and positioned to cover substantially the curved theoretical time spaced deflection line calculated to compensate for the different circumferential sweep velocities of said beam segments, so that energy of each beam segment is transmitted successively to said beam responsive means in time displaced relationship directly proportional to the amount of energy applied to said deflecting electrode whereby distortion of said proportion due to said different velocities of said beam segments is prevented.

15. A multichannel pulse modulator comprising means to produce a beam of electrons, means to cause said beam to have a circular sweep movement, means to divide the beam into a successive plurality of segments with respect to said sweep movement, a plurality of signal channel input circuits, means associated with each of said input circuits to control deflection of said beam successively during its sweep movement according to the increment of the input signal on said circuits, beam responsive means, and a shielding means positioned between said beam responsive means and said means for deflecting said beam segments, said shielding means having apertures herein corresponding to each beam segment through which that beam segment passes, each of said apertures being long and narrow and disposed at an acute angle to the radius through the center of said tube and spaced slightly in the opposite direction of the sweep movement of said beam segment whereby the theoretical time spaced deflection curved line for traverse by the end of the beam segments is substantially bracketed so that the entry from each said beam segments is transmitted successively to said beam responsive means in a time displaced relationship substantially directly proportional to the amount of energy applied to said deflecting electrode and hereby produces pulses of energy modulated ac-

cording to the corresponding signal deflection of said beam segments.

16. In a multichannel pulse modulator, means to produce a beam of electrons, means to cause the beam to have a given sweep movement, channel commutating means for producing beam segments with respect to said sweep movement, a plurality of signal channel input circuits, means associated with said input circuits to control deflection of the beam segments successively during its sweep movement according to increment of the input signal of said circuit, and beam responsive means to produce pulse of energy time modulated according to the corresponding signal deflections of said beam segments; said beam responsive means including means for presenting narrow target areas for impingement by electrons of said beam to produce current flow, the central portion of said areas being arranged at

10 an arcuately disposed acute angle toward and to the direction of signal deflection of said beam, and the ends of said areas being arranged substantially parallel to the direction of said deflection.

15 17. A multichannel pulse modulator comprising means to produce a beam of electrons, means to cause said beam to have a circular sweep movement, a plurality of signal channel input circuits, means associated with said input circuits to control deflection of the beam successively during its sweep movement according to increment of the input signal of said circuit and beam responsive means to produce pulses of energy modulated according to the corresponding signal deflection of

20 said beam; and shielding means positioned between said beam responsive means and said deflecting means, said shielding means having apertures therein through which said beam passes, said apertures being so proportioned respecting

25 length and breadth and so positioned with respect to the motions of said beam to transmit the energy in the beam successively to said beam responsive means in a time displaced relationship substantially directly proportional to the amount

30 of energy applied to said deflecting means; said deflecting means including a major electrode disposed centrally of the sweep path of said beam and a plurality of minor electrodes disposed in sequential relation along the sweep path of said

35 beam spaced from said major electrode; and said beam responsive means having the shape of an obtuse cone positioned axially of said tube, the conical sides of which are substantially perpendicular to said beam as it is deflected around the tube.

40 18. A multichannel pulse modulator comprising means to produce a beam of electrons, means to cause said beam to have a circular sweep movement, a plurality of signal channel input circuits, means associated with said input circuits to control deflection of the beam successively during its sweep movement according to increments of the input signal of said circuits, and beam responsive means to produce pulses

45 of energy modulated according to the corresponding signal deflection of said beam; said means for controlling signal deflection of the beam including a major electrode disposed centrally of the sweep path of said beam and a plurality of minor electrodes disposed in sequential

50 relation along the sweep path of said beam and spaced from said major electrode so as to be a greater distance from the major electrode at its beam outlet end than at its beam inlet end to provide passage for the beam and its deflection

therebetween, and means for connecting said circuits each to one of said small electrodes.

19. A multichannel pulse modulator comprising means to produce a beam of electrodes, means to cause said beam to have a circular sweep movement, a plurality of signal channel input circuits, means associated with said input circuits to control deflection of the beam successively during its sweep movement according to increments of the input signal in such circuits, and beam responsive means comprising a shielding means and a beam responsive plate to produce pulses of energy modulated according to the corresponding signal deflection of said beam, both of said shielding means and said plate comprising obtuse cones positioned axially of said tube, the conical sides of which are substantially tangent to the beam as it is deflected around the tube.

20. A multichannel pulse modulator comprising means for producing a beam of electrons, means to cause said beam to have a circular sweep movement, a plurality of signal channel input circuits, means associated with said input circuits to control deflection of the beam successively during its sweep movement according to increment of the input signal of said circuits, and beam responsive means to produce pulses of energy modulated according to the corresponding signal deflection of said beam, said beam responsive means comprising an obtuse cone positioned axially of said tube, the conical sides of which are substantially tangent to said beam as it is deflected around the tube.

21. A multichannel pulse modulator comprising means to produce a beam of electrons, means to cause said beam to have a circular sweep movement, a plurality of signal channel input circuits, means associated with said input circuits to control deflection of the beam successively during its sweep movement according to increment of input signal in such circuits, and beam responsive means comprising a shielding means and a beam responsive plate to produce pulses of energy modulated according to the corresponding signal deflection of said beam, said shielding means comprising an obtuse cone positioned axially of said tube, the conical sides of which are substantially perpendicular to the beam as it is deflected around the tube.

22. A cathode ray tube comprising: means to produce a beam of electrons, means to cause said beam to have a circular sweep movement, means to divide the beam into a successive plurality of segments with respect to said sweep movement, a plurality of signal channel input circuits, means associated with said input circuits to control deflection of the beam successively during its sweep movement according to the increment of the input signal of said circuits, means responsive to said beam segments, shielding means positioned between said beam responsive means and said deflecting means; said shielding means having apertures therein through which said

beam segments pass, said apertures being so proportioned respecting length and breadth and so positioned with respect to the motion of said beam segments to transmit energy of each beam segment successively to said beam responsive means in time displaced relationship successively directly proportional to the amount of energy applied to said deflecting electrodes; and said means for controlling the deflection of said beam segments including means to control the acceleration of the beam, and means responsive to the changes in acceleration of the beam to deflect the beam with respect to said beam responsive means.

23. A multichannel modulator comprising: means to produce a beam of electrons, means to cause said beam to have a circular sweep movement, means to divide the beam into a successive plurality of segments with respect to said sweep movement, a plurality of signal channel input circuits, means associated with said input circuit to control deflection of the beam successively during its sweep movement according to the increment of the input signal of said circuits, means responsive to said beam segments, and shielding means positioned between said beam responsive means and said deflecting means, said shielding means having long and narrow arcuate apertures therein corresponding to each beam segment through which said beam segments pass, said apertures being shaped and positioned to cover substantially the curved theoretical time shaped deflection line calculated to compensate for the different circumferential sweep velocities of said beam segments, so that the energy of each beam segment is transmitted successively to said beam responsive means in time displaced relationship directly proportional to the amount of energy applied to said deflecting means whereby distortion of said proportion due to said different velocities of said beam segments is prevented; and said deflecting means including means to control the acceleration of the beam, and means responsive to the changes in acceleration of the beam to deflect the beam with respect to said beam responsive means.

EMILE LABIN.
